REFRIGERATING METHOD AND APPARATUS

Charles W. Stratford, Kansas City, Mo., assignor
to Stratford Development Corporation, Kansas
City, Mo., a corporation of Delaware

Application January 18, 1937, Serial No. 121,033

6 Claims. (Cl. 62—126)

My invention relates to a refrigerating method and apparatus, and more particularly to a refrigerating method and apparatus for use in refrigerating hydrocarbon oils undergoing treatment, in which exothermic reactions take place, as, for example, the treatment of hydrocarbon oil with sulphuric acid.

One object of my invention is to provide a method of and apparatus for maintaining a constant maximum temperature to which the chemical reaction between sulphuric acid and hydrocarbon oil is allowed to proceed.

Another object of my invention is to provide a method of and apparatus for, in the processing of materials in which an exothermic reaction takes place, absorbing the heat of reaction at as high a temperature level as is possible without exceeding the maximum temperature to which the reactants shall be allowed to proceed.

Another object of my invention is to provide a method of and apparatus for, in a refrigerating system, utilizing the highest possible suction pressure of refrigerant fluid compressors of a refrigerating system, thereby reducing the range through which the refrigerant fluid must be compressed, thereby enabling the handling of greater loads for a compressor of a given size or the saving of power consumption by permitting the use of smaller equipment.

Another object of my invention is to provide a method of and apparatus for refrigerating in which the heat transfer rate of a chiller-heat exchanger is increased by continuously evaporating a liquefied refrigerant gas from a heat exchanger coil positioned within an evaporating zone, through which heat exchanger coil fluid to be processed is passed.

A further object of my invention is to provide a method of and apparatus for refrigerating in which a high heat transfer rate within a heat exchange zone is maintained by the circulation of a large quantity of liquefied refrigerant gas.

A still further object of my invention is to provide a method of and apparatus for regulating the temperature of reactants in response to the final temperature of these leaving the treating zone.

Other and further objects of my invention will appear from the following description.

For purposes of clarity and convenience, I will describe my method and the operation of my apparatus with reference to ammonia gas as the refrigerant fluid. It is to be understood, however, that this is only for the purpose of clarity and illustration, and that any suitable refrigerant fluid, such as ethyl chloride, sulphur dioxide or the like, may be used.

As is well known to the art, in a mechanical refrigerating system a refrigerant gas is compressed, the heat of compression removed by heat exchange in what is known as a "condenser". The condensed refrigerant gas (which is then usually in a liquid state) is then expanded through an expansion valve into a zone of reduced pressure, as for example, into an elongated conduit in the form of a coil which is usually termed the refrigerating coil. Upon expansion the liquefied refrigerant reassumes a gaseous state and passes to the compressor for re-compression and recycling. The efficiency of an ammonia compressor will vary as a function of the suction pressure.

My apparatus and method has in view the absorbing of the heat of reaction as rapidly as it is created in order to reduce the temperature range, whereby I am enabled to operate my system at a high suction pressure of the compressor.

The accompanying drawing represents a diagrammatic view of a refrigerating system for contacting hydrocarbon oil with acid in the acid treatment thereof, in which the temperature is controlled by refrigeration, embodying apparatus of my invention which is capable of carrying out the process of my invention.

While my process and apparatus will be described with reference to hydrocarbon oils for purposes of illustration, it is to be understood that it is applicable to any chilling or refrigerating use.

The hydrocarbon distillate to be treated is stored in tank 1, from which it is pumped by pump 2 through line 3 to a settling tank 4 in which bottom settling, water and other impurities are permitted to settle and periodically drained through line 5, controlled by valve 6. The distillate after settling is withdrawn from the settler 4 through line 7 and passes through heat exchanger 8, in which the oil is cooled by heat exchange against the treated distillate entering heat exchanger through line 9 and leaving it through line 10. The treated distillate, as will be hereinafter seen, has been refrigerated and after leaving the separating step in which the treating agent is separated, is pumped through line 9. The heat exchange is usually sufficient to lower the temperature of the distillate considerably, for example, to say 40° F. for purposes of illustration. The cooled distillate leaves the heat exchanger through line 11 and may be passed directly to the distillate induc-

- tion line 15 of heat exchanger 12 through line 13, or through cooling coil 14, depending upon the position of valve 16 controlling line 13, and the position of valves 17 and 18 controlling coil 14. If desired, a portion of the distillate may be passed both through line 13 and through coil 14 by partially opening valves 16, 17 and 18. Coil 14 is positioned within a chilling chamber 19, which will be hereinafter more fully described.
- 10 The distillate to be chilled is admixed in line 15 with the treating agent, as for example acid, being pumped from any suitable supply by pump 22, through line 20, controlled by valve 21.
- 15 The mixture of treating agent and distillate enters the heat exchanger 12 in which the heat of reaction is removed, it being my purpose to remove the heat of reaction as fast as it is liberated and to employ as small a mean temperature difference as is permitted by the amount 20 of heat transfer surface and the velocity of flow of the refrigerant and reacting mixture through the heat exchanger. The chilled distillate-acid mixture leaves the heat exchanger 12 through line 23, which is fitted with a thermometer well 24 in which the temperature responsive element of a temperature controller 25 is positioned. The temperature controller is adapted to control valve 26 which governs the pressure in chill chamber 19, as will be more fully pointed out hereinafter.
- 30 The refrigerating system comprises an ammonia compressor 27 driven by any suitable prime mover, such as an electric motor 28. The gaseous ammonia to be compressed enters the compressor through suction line 29, and leaves the compressor in compressed condition through line 30 and passes into condenser 31, which is supplied with a cooling medium through line 32, which leaves through line 33.
- 35 In the condenser 31 the compressed ammonia gas will be liquefied and will leave in liquefied condition through line 34 and pass into receiver 35, from which it is withdrawn through line 36 and discharged through liquid level control 37 into the chiller 19. The liquid level control is 40 well known to the art and in general comprises a valve controlled by the level of the liquid within a vessel. In the instant case, the liquid level control 37 will maintain a body of liquid ammonia 38 within the chill chamber 19. When 45 the desired level is reached, the liquid level control operates to prevent the induction of further liquid ammonia. When the level of the ammonia within chill chamber 19 drops, the level control operates to permit further ammonia to 50 flow into the chill chamber to bring the level to the desired point.
- 55 An ammonia pump 39 withdraws liquid ammonia from chill chamber 19 through line 40 and discharges it through line 41, through the heat exchange elements within heat exchanger 12. The rate of flow is such that more liquid ammonia will be pumped through the heat exchange elements in heat exchanger 12 than will be vaporized for the given heat exchange surface, so that there will be withdrawn from heat exchanger 12 through line 42 a mixture of gaseous or vaporized ammonia and liquid ammonia. This is discharged into chill chamber 19 through a spray head 43. Liquid ammonia falling downwardly, as indicated 60 by the arrows, allows separated gaseous ammonia to be withdrawn through line 44 for passage through control valve 26 into line 29 to the suction of the compressor.
- 65 Considering now the operation of my system with valves 17 and 18 closed, and valve 16 open,

all of the hydrocarbon distillate to be treated will bypass chilling coil 14. Let us assume that it is desired to conduct the treating reaction so that the outlet temperature of the distillate-acid mixture will not be in excess of 20° F. and the temperature of the incoming distillate to be treated has been pre-cooled by heat exchanger 8 to a temperature of 40° F.

As the outlet temperature of the distillate-acid mixture tends to exceed 20° F., the arrangement is such that pressure controller 25 is operated to reduce the air pressure impressed upon control diaphragm 45 through line 46 to permit valve 26 to open to a greater extent. This reduces the back pressure upon the chill chamber 19 and permits a larger volume of liquid ammonia to evaporate, which in turn lowers the temperature of the body of liquid ammonia 38, as well as permitting a greater expansion of ammonia within the heat exchange elements of heat exchanger 12. Since the heat transfer surface of the heat exchange elements within heat exchanger 12 is limited, it will be obvious that under certain conditions the back pressure in the ammonia system of the heat exchanger may be reduced to such a point that compressor 27 will be operating under a considerably lowered suction pressure. As pointed out hereinbefore, this renders the operation of the ammonia compressor inefficient.

Let us now consider the operation with the valve 16 closed, and valves 17 and 18 open. The distillate will be further chilled by heat exchange with ammonia being sprayed over the coil from spray head 43. The temperature will be lowered by the evaporation of ammonia through heat supplied from the distillate by heat exchange. This reduction in temperature can be effected without decreasing the back pressure of the ammonia system in heat exchanger 12, since in effect coil 14 acts as the heating coil of a still and the evaporation of additional ammonia by transfer of heat from the coil 14 to the liquid ammonia being sprayed thereover will in effect raise the suction pressure at which the ammonia gas is passed to the compressor 27.

Since the distillate is much greater in volume than the treating agent, and the distillate is pre-cooled, a much smaller load is placed upon the heat exchanger 12. Should the temperature tend to be lowered under the desired treating temperature of 20° F., the temperature responsive element in well 24 will operate temperature controller 25 to increase the air pressure impressed upon diaphragm 45 through line 46. This will cause the valve 26 to tend to close, thus further increasing the back pressure upon the chill chamber 19 and enabling the compressor to operate at a higher suction pressure and thus more efficiently. Should the temperature of the distillate-acid mixture tend to exceed the desired treating temperature of 20° F., the valve 26 is moved to open somewhat, decreasing the back pressure upon the chill chamber 19. This enables the liquid ammonia being sprayed over the coil 14 to evaporate to a greater extent, that is, a larger quantity of ammonia will be evaporated by the heat supplied from the distillate in coil 14. This in turn will cool the distillate to a greater extent and will, in addition, permit a greater quantity of heat to be removed in heat exchanger 12, thus enabling the additional heat load to be carried at a smaller decrease of back pressure than would otherwise be possible.

It will be apparent that by the use of my

method and apparatus the back pressure in the chill chamber will vary as an exponential function of the outlet temperature of the acid-distillate mixture, instead of as an arithmetical function of said temperature. In this manner it will be obvious to those skilled in the art that I have provided a very flexible refrigerating system in which a refrigerating heat exchanger of a given size in connection with a refrigerating system of a given rating, can be used to carry a refrigerating load far in excess of what would otherwise be possible. It will be obvious, therefore, that I am thus enabled to use smaller size equipment both with respect to the refrigerating heat exchanger and the ammonia compressor, thus enabling savings not only in installation cost, but also in operating cost. This saving is largely effected by enabling a given ammonia compressor to operate at its most efficient point.

It is to be understood, of course, that my method and apparatus can be used in connection with any refrigerating problem where it is desired to refrigerate any substance or mixtures of substances and that I have described my method and apparatus with respect to the acid treating of hydrocarbon oil for the purpose of illustration only, and not by way of limitation.

It will be understood that certain features and sub-combinations are of utility and may be employed without reference to other features and sub-combinations. This is contemplated by and is within the scope of my claims. It is further obvious that various changes may be made in details within the scope of my claims, without departing from the spirit of my invention. It is, therefore, to be understood that my invention is not to be limited to the specific details shown and described.

Having thus described my invention, what I claim is:

1. In a refrigerating system, a chamber, means for supplying liquefied gaseous refrigerant to said chamber, a heat exchanger, a heat exchange means positioned within said chamber and means for circulating a liquefied refrigerant gas from said chamber through said heat exchanger and back into said chamber, and means for passing returned liquefied refrigerant gas over said heat exchange means in said chamber.
2. In a refrigerating system, a chamber, means for supplying liquefied refrigerant gas to said chamber, a refrigerant gas outlet from said chamber, a valve for controlling said outlet, a heat exchanger, means for introducing fluid to be refrigerated into said heat exchanger, means for withdrawing refrigerated fluid from said heat exchanger, means for circulating liquefied refrigerant gas from said chamber through said heat exchanger back into said chamber, and means responsive to the temperature of the re-

frigerated fluid leaving said heat exchanger for controlling said valve.

3. In a refrigerating system, a chamber, means for supplying liquefied refrigerant gas to said chamber, heat exchange means positioned in said chamber, a heat exchanger, means for introducing fluid to be refrigerated into said heat exchange means, means providing communication between said heat exchange means and said heat exchanger, means for withdrawing refrigerated fluid from said heat exchanger, means for circulating liquefied refrigerant gas from said chamber through said heat exchanger back into said chamber, a refrigerant gas outlet from said chamber, a valve for controlling said outlet and means responsive to the temperature of the refrigerated fluid leaving said heat exchanger for controlling said valve.

4. A method of refrigerating fluids including the steps of passing a fluid to be refrigerated in heat exchange relation with a liquefied refrigerant gas, permitting a portion of said liquefied gas to gasify during said heat exchange step, maintaining a body of liquefied refrigerant gas in a confined zone under a predetermined pressure, circulating liquefied refrigerant gas from said zone through said heat exchange step and back to said zone, withdrawing gasified refrigerant gas from said zone and controlling the pressure in said zone in response to the temperature of the fluid being refrigerated.

5. A method as in claim 4 in which the fluid being refrigerated is precooled by heat exchange with a liquefied refrigerant gas in said confined zone whereby heat supplied from the fluid to be refrigerated will evaporate a portion of said liquefied refrigerant gas without decreasing the pressure in said confined zone.

6. In a method of contacting a hydrocarbon oil and a treating agent at reduced temperatures, including the steps of admixing said hydrocarbon oil and said treating agent and permitting them to react in a refrigerated heat exchange zone, maintaining a body of liquefied gaseous refrigerant, continuously withdrawing liquefied gaseous refrigerant from said body and introducing it into said refrigerated zone in heat exchange relation with said reacting oil and treating agent, withdrawing the refrigerant fluid from said heat exchange zone and separating it into gas and liquid, and continuously returning said liquid to said body of liquefied refrigerant gas, wherein said separated liquid is passed in heat exchange relation with hydrocarbon oil being charged to the process in a heat exchange zone maintained under super-atmospheric pressure, whereby to evaporate additional liquefied refrigerant gas by heat supplied from the charge without decreasing the pressure in said heat exchange zone.

CHARLES W. STRATFORD.
